Primary Examiner—B. J. Bullock
Attorney, Agent, or Firm—Wenderoth, Lind & Ponack[57] **CLAIM**

The ornamental design for a board clamp, as shown and described.

DESCRIPTION

FIG. 1 is a front elevational view of a board clamp showing my new design;

FIG. 2 is a right side elevational view thereof;

FIG. 3 is a top plan view thereof;

FIG. 4 is a bottom plan view thereof;

FIG. 5 is a cross-sectional view taken in the direction of the arrows on line 5—5 in FIG. 1;

FIG. 6 is a cross-sectional view taken in the direction of the arrows on line 6—6 in FIG. 1; and,

FIG. 7 is a front elevational view thereof in its position of use, the broken line showing of the boards being for illustrative purposes only.
